US0D1075966S

(12) **United States Design Patent** (10) **Patent No.:** **US D1,075,966 S**
(45) **Date of Patent:** **** May 20, 2025**

(54) **DOLL**

(71) Applicant: **Jia Liao**, Shaoyang (CN)

(72) Inventor: **Jia Liao**, Shaoyang (CN)

(**) Term: **15 Years**

(21) Appl. No.: **29/980,035**

(22) Filed: **Dec. 21, 2024**

(51) LOC (15) Cl. **21-01**

(52) U.S. Cl.

USPC **D21/617**

(58) **Field of Classification Search**

USPC D21/398, 576, 584, 587, 588, 613, 617,
D21/625, 627, 630, 653; D11/158

CPC ... A63H 3/02; A63H 3/04; A63H 3/00; A63H
33/004
